[57] ABSTRACT

Pipe cleaning fluid comprises digallic acid, and other impurities derived from ground briar root and the like, dissolved in a suitable solvent.

3 Claims, No Drawings

PIPE CLEANING FLUID

SUMMARY OF THE INVENTION

It is well known that nicotine is among those substances which accumulate in the passageways of pipes and cigarette holders, and in the bowls of pipes, and that this accumulation decreases the harmfulness of the smoke.

However, over a long period of time, this accumulation reduces the cross-sectional area of the passageways available for the passage of smoke.

It then becomes necessary to periodically clean these passageways, as well as the metallic filters, which are commonly incorporated therein, so as to make the pipe or cigarette holder draw easily again.

It is known that nicotine, which is one of the natural alkaloids of tobacco, is a violent poison which is soluble in alcohol, in ether and in gasoline.

From among these three solvents, it is logical to think first of ethyl alcohol for dissolving the nicotine accumulated in the passageways, because of the disagreeable odor of ether and the oily nature of gasoline.

Unfortunately, regardless of the concentration of a commercial alcohol, even if the material defining the inner passageway of a pipe or a cigarette holder does not actually retain some of the alcohol because of rapid vaporization of this solvent in the air, it retains after having been in contact with the alcohol a characteristic alcohol odor which is due to the impurities dissolved therein, and which impregnates the material after evaporation of all the alcoholic solvent.

The present invention diminishes these disadvantages and is characterized by the fact that tannin, that is to say digallic acid, is dissolved in a suitable solvent, which may be alcohol, and is adapted to clean pipes and cigarette holders. This tannin reacts with the nicotine accumulated in the pipes or the cigarette holders at the moment at which the nicotine dissolves in the alcohol, to form an insoluble harmless compound which eventually falls to the bottom of the container in which one soaks the cleaners used to frictionally remove the accumulated nicotine, and in which the insoluble compound which results from the reaction between the nicotine and part of the tannin contained in the alcoholic solution then accumulates.

Experience has shown that it is necessary to macerate in alcohol for a sufficient time, for example a month, the sawdust of certain vegetative products, such as nutgall, oak bark, briar root. The tannin which is found therein becomes dissolved in the alcohol, together with certain other constituents contained in these vegetative products. If the resulting solution is then applied to the nicotine accumulated in a pipe or cigarette holder for cleaning purposes, it is found that the aroma of the tannin which has not reacted with the nicotine and which remains in the alcoholic solution, as well as the aroma of the impurities from said vegetative products, masks that of the normal impurities in the alcohol when these different impurities, after vaporization of said alcohol, impregnate the material of which the pipes and cigarette holders are made, thus considerably reducing the deterioration in the natural aroma of the tobacco smoke.

In a preferred embodiment of the invention the tannin in solution in the alcohol is obtained by macerating the sawdust of very old briar root which has been perfectly dried.

In this case, independently of the aroma of the tannin, that of the impurities from the briar root makes it possible to reconstitute a taste very comparable to that of the smoke of a pipe which has not been in contact with alcohol and is made of this material.

Since pure tannin is soluble not only in alcohol but partially soluble in water, it is possible to use any commercial alcohol having a titer equal to at least 40° and less than 90°.

10 The volume of sawdust is preferably between one-fourth and one-half the volume of the alcoholic solvent.

However, the applicant has found that, even when using the sawdust of briar root, it is not always possible to completely mask the particular aroma due to the impurities in the alcohol used, which impregnate said pipes or said cigarette holders after complete vaporization of the alcohol. To obtain better results it is recommended to add to the alcoholic solution obtained by macerating the sawdust and by decantation, a tiny trace of essential oil of tobacco flower, which product is known to all perfumers and is sold by specialized manufacturers or wholesale druggists.

25 It is easy to understand that the use of a trace of another essential oil involves the risk of rendering the taste of the tobacco smoke less natural. It will also be noted that the duration of the macerating process and the quantity of sawdust to be macerated may be varied with respect to the volume of alcohol used within broad limits, dependent upon whether the vegetative product used is more or less rich in tannin.

30 In like manner, the total quantity of tannin dissolved in the alcohol must be sufficient to be able to react with the quantity of nicotine accumulated, but, on the other hand, if this concentration is too great it may also impair the aroma of the tobacco smoke, in the absence of a small quantity of essential oil of the tobacco flower capable of overcoming this disadvantage.

Finally, it will be readily understood that, independently of the tannin, it is preferable to use the sawdust of oak bark rather than the gallnut, so as to avoid impregnating the pipes and cigarette holder to be cleaned with strongly aromatic impurities which are capable of impairing the taste of the tobacco smoke after this 45 cleaning. It should be noted that, independently of its use for the cleaning of encrusted pipes and cigarette holders, the product according to the invention may be used to preventively impregnate the superficial pores of the passageways of these pipes or cigarette holders so that, after complete evaporation of the solvent used, the particles of tannin dissolved therein are deposited on the walls of these pores. It is easy to understand that, in this case, the nicotine contained in the smoke, instead of being immediately frictionally deposited upon walls of these passageways is at least partially neutralized by the presence of the tannin retained in said pores and is transformed into an inoffensive product, thus delaying the moment at which nicotine itself is deposited and accumulated in these passageways.

55 60 By cleaning the passageways very frequently with the aforesaid alcoholic solution it is possible to avoid any encrustation and any accumulation of nicotine, while increasing the denicotinizing capacity of these passages.

65 It will be appreciated that the process which has been described may be modified as to detail, with certain products replaced by equivalent products, without

thereby departing from the basic principles of the invention.

What is claimed is:

1. The scale-removing solution for cleaning pipes and cigarette holders, which is produced by macerating dry briar root particles containing tannin in ethyl alcohol, the volume of said particles being equal to at least one-fourth of the volume of alcohol, and drawing

off the solution thus obtained.

2. Solution as claimed in claim 1 in which the volume of said particles is at least equal to the volume of said alcohol.

3. Solution as claimed in claim 1 which includes a trace of the essential oil of tobacco flower.
